J. K. MACDONALD

GREENHOUSE

Filed Sept. 23, 1927

Inventor

John K. Macdonald.

By Hartwell Paton.
Attorney

UNITED STATES PATENT OFFICE.

JOHN K. MACDONALD, OF RIDGEWOOD, NEW JERSEY, ASSIGNOR TO HITCHINGS & COMPANY, OF ELIZABETH, NEW JERSEY, A CORPORATION OF NEW JERSEY.

GREENHOUSE.

Application filed September 23, 1927. Serial No. 221,478.

This invention relates to improvements in roof construction for green-houses, or similar buildings, usually having glazed covering elements, or other material, more 5 or less subject to the influence of varying temperatures.

One of the salient features of the invention resides in the provision of a flexible mounting rigidly connected to certain of the 10 structural elements of the roof and joined to the sash-bars thereof in a manner to permit longitudinal movements of the latter without distortion of the covering elements.

Another object of the invention is expressed in the novel and unique method of 15 so connecting said flexible mounting, or resilient members, with the sash-bars so that the latter may unrestrictively flex laterally in order to accommodate the expansion of 20 said covering elements.

Still another object of the invention is to provide a resilient mounting for the covering elements and sash-bars which is featured by its simplicity of construction and 25 its efficiency in operation.

Still further features and advantages flowing from my invention will be readily understood on inspection of the accompanying drawing, wherein:

30 Figure 1 is a sectional detail of a portion of a roof construction, embodying my invention, and illustrative of one of the forms thereof.

Figure 2 is a transverse sectional view 35 taken substantially on the line 2—2 of Fig. 1.

Figure 3 is a view like unto Fig. 1, but depicting another form of the invention.

Figure 4 is a transverse sectional view 40 taken on the line 4—4 of Fig. 3; and

Figure 5 is a sectional view taken on the line 5—5 of Fig. 4 and illustrating the formation of this particular flexible support.

45 In the accompanying drawing, forming a part of this specification, let 10 denote the supporting rafters of the roof structure, which are suitably connected by a series of stringers 11 disposed at right angles therewith throughout the structure. It will, of course, be understood that in accordance with general practice said rafters 10 may be connected at one end to the ridge pole of the structure, its lower end being suit-

ably supported by posts, or the like, included in the sides of the building.

55 The covering elements 12 are preferably composed of glazed material, arranged in sections, having their several lateral edges supported by a plurality of sash-bars 13 disposed above, and spaced from said rafters 10 and stringers 11, through the intermediary of resilient or flexible members 14 having their lower ends suitably secured to said stringers, as indicated at 15.

60 Upon inspection of Fig. 2 it will be noted that each of said sash-bars 13 is substantially inverted U-shaped in cross-section, the extremities of the leg portions being bent laterally to present flanges 16, directly supporting the edges of said covering elements 12. Said sash-bars are constructed of relatively thin material and it is obvious the lateral movements of the covering elements 65 may be accommodated by the flexing of the leg portions. In view of this construction the expansion and contraction of said covering elements is compensated for, but it is quite apparent that the movements of the sash-bars themselves must be accommodated 70 as the same are equally as susceptible to the changing climatic conditions as the covering elements themselves.

75 To meet these conditions and to obviate the deteriorating effects flowing therefrom, my predecessors in this art have proposed and adopted means of connection between the sash-bars and the stringers, whereby a sliding movement is effected. The defects of such an arrangement are obvious, the most striking of which being loose connection necessarily existing between said sash-bars and their supports and the tendency of such a connection to become clogged and fail to operate.

80 In order to cure these defects I propose to support said sash-bars by means of the resilient members 14, which are inherently flexible and yielding in view of their relative thinness and their leaf-spring-like structure. 85 As aforesaid the lower ends of said members 14 are rigidly connected to the stringers 11, while their upper ends are preferably shouldered, as indicated at 17, to define a reduced portion 18 insertable within apertures 19, 90 formed in the top portions of the sash-bars, and secured by a nut 18^a. This method of connection has been adopted for the sake of 95

simplicity and it is quite manifest that I have substantially a rigid connection existing at both ends of each of said members 14. The longitudinal movements of the sash-bars 5 are readily accommodated through the springy action of said members 14 which are capable of flexing in whichever direction said sash-bars move and which are equally capable of returning to normal position.

10 The form disclosed in Figs. 3 and 4 is somewhat similar to my preferred form. In this instance the flexible member 20 is provided with a thinned portion 21 intermediate the lower end of said member, which is 15 cured to the stringers by means of bolts, as indicated at 22, the upper end of which being shouldered, as indicated at 23, to define a tenon 24 passing through an aperture 25 in the sash-bars. If desired, said tenon 20 24 may be provided with threads in order to receive a nut 26.

As in my preferred form the sash-bars absorb the expansion of the covering elements and obviously the thinned portion 21 of said members 20, yieldably react to the changing longitudinal movements of said bars. In view of the relatively thicker extremities of this form a more substantial connection between sash-bars and stringers may be effected.

30 Each of the members 14 and 20 are positioned within the sash-bars in a manner not to interfere with the inward deflection of the leg portions thereof, and it is apparent that 35 the collection of water upon the inner sides

of the sash-bars may descend upon the lower faces of the flanges 16 and escape to a point adjacent the eaves or other place of discharge. Under no circumstances can this 40 collected water attach to the members 14 and 20, or the stringers, positioned therebeneath.

I claim:

1. In a roof construction including stringers and channel-like sash-bars for supporting covering elements, means of resilient 45 material connecting a sash-bar and a stringer.

2. In a roof construction including stringers and channel-like sash-bars for supporting covering elements, means of resilient 50 material fixedly connecting a sash-bar and a stringer and adapted to flex between its points of connection to accommodate the longitudinal movements of said sash-bar.

3. In a roof construction including 55 stringers and channel-like sash-bars for supporting covering elements, means for connecting a sash-bar and a stringer, said means being thinned between its points of connection to provide a flexible connection between 60 said sash-bar and a stringer.

4. In a roof construction including 65 stringers and channel-like sash-bars for supporting covering elements, means of resilient material connecting a sash-bar and a stringer, said means having its upper end shouldered to abut the adjacent inner face of a sash-bar and presenting a reduced portion insertible through said sash-bar.

JOHN K. MACDONALD.
